tion of Illinois

Application May 3, 1946, Serial No. 667,070

9 Claims. (Cl. 15—83)

1

The present invention relates generally to improvements in street sweeping machines and more especially concerns a novel main sweeper broom assembly and control means therefor.

Among the objects of the invention is the provision of improved means in a power sweeper broom assembly or unit for relieving the bristles of the main rotary sweeper broom from excessive wear due to the weight of the broom structure.

Another object of the invention is to provide improved self-adjusting means for compensating for the weight of a main power sweeper broom assembly and which acts uniformly in all operative positions of the broom, being especially adaptive to the conditions involved in the progressive lowering of the broom as the bristles wear down in the course of prolonged operation of the broom.

Still another object of the invention is to provide improved means for actuating a power sweeper broom assembly between operative and inactive positions.

A further object of the invention is to provide improved dirt-confining side shoe means cooperative with the main sweeper broom.

A still further object of the invention is to provide an improved power sweeper broom assembly including side dirt shoe structure and novel integrating means for elevating and depressing the shoe structure with the sweeper broom.

According to the general features of the invention, a rotary cylindrical main power sweeper broom is supported rotatably by pivotally mounted broom-supporting arms and is adapted to be driven from the motive power source of the self-propelled sweeping machine, wearing down of the bristles of the broom being minimized by compensating the weight of the broom assembly by an arrangement of springs in such a manner as to relieve the bristles from the full weight thereof but yet allowing the bristles to make efficient sweeping contact with the roadway being swept.

Another feature of the invention resides in the provision of a main cylindrical power sweeper broom assembly in which as the broom bristles gradually wear down and the broom diameter decreases so that the broom axis drops lower, the novel compensating spring means absorbs the major proportion of the weight of the broom assembly substantially uniformly in any operative position of elevation thereof.

In accordance with another feature of the invention an improved operating device is provided for elevating the main sweeper broom to inactive position as desired, including a hydraulic op-

2

erator and an efficient leverage and linkage system.

According to still another feature of the invention, an improved cooperative relationship is afforded of the main power sweeper broom assembly and an improved side dirt guard or shoe assembly, the latter assembly being connected by an appropriate self-releasing linkage to be elevated from work engagement with the roadway when the broom assembly is elevated to inactive position and having independent relative movement during sweeping operation for road contour riding.

Other objects, features, and advantages of the present invention will be readily apparent from the following detailed description of a preferred embodiment of the invention taken together with the accompanying five sheets of drawings, in which:

Figure 1 is a more or less schematic side elevational view of a street sweeping machine embodying the features of the present invention;

Figure 2 is an enlarged fragmental side elevational view of the sweeper broom assembly and cooperating dirt shoe assembly at the right side of the machine;

Figure 3 is a fragmental enlarged horizontal sectional detail view taken substantially along the line III—III of Figure 1;

Figure 4 is a more or less conventionalized fragmental vertical sectional view taken substantially along the line IV—IV of Figure 2;

Figure 5 is a fragmentary detail elevational view taken substantially in the plane of line V—V of Figure 4;

Figure 6 is a fragmentary plan view of the cylindrical main sweeper broom taken substantially on the line VI—VI of Figure 2;

Figure 7 is a fragmentary plan view of the upper portion of one of the broom supporting arms showing details of the length adjusting structure of the arm;

Figure 8 is a side elevational view of that portion of the broom supporting arm shown in Figure 7; and

Figure 9 is a fragmentary plan view, on an enlarged scale, of the dirt guard or shoe structure, taken substantially along the line IX—IX of Figure 2.

The sweeper broom assembly of the present invention is especially adapted for use in a small size or "baby" street sweeping machine on the order of that disclosed in my copending application for patent Serial No. 646,525, filed February 9, 1946, now Patent No. 2,505,199, issued April

25, 1950. Such a sweeping machine comprises a front engine or power section 15 and a rear or sweeping section 16 with a cooperatively intervening operator's cab 17 (Fig. 1). In support of the power section 15 is a framework or chassis comprising structural beams 18 which also carry the operator's cab 17 and are suitably united with the rear sweeping section 16 of the machine. The sweeping section may be constructed principally or entirely from sheet metal including side plates 19 having forwardly extending wing portions 20 which are secured to the chassis beams 18 as best seen in Figs. 1 and 3. The chassis beams 18 may converge forwardly and support a steering wheel structure 21. Supporting the sweeping section 16 are wheels 22 (one at each side of the machine) which may be driven in any suitable manner from the power section 15 under the control of the operator through the medium of a transmission system including a shifting lever 23 in the cab 17. A splash guard and closure plate structure 24 at each side of the sweeping section 16 partially encloses the associated wheel 22 and other operating structure for the machine.

Mounted for operation partially between the forward portion of the rear wheels 22 and accessible through appropriate cut out openings 25 in the lower portions of the side plates 19 is a main sweeper broom 27 (Figs. 1, 2 and 6) which is of the rotary cylindrical type embodying any preferred construction and comprising radial bristles 28 mounted on a core (not shown) supported by an axial shaft 29, the bristles being confined at the ends of the broom by respective end plates 30.

Rotatably supporting the sweeper broom axle 29 is a pair of preferably identically constructed arms 31 provided with preferably separable and adjustable bearing structure 32 engaging the broom shaft. Self-adjustment of the sweeper broom 27 to the contours of the street being swept, as well as swinging of the broom into and out of operative position is provided for by mounting the arms 31 pivotally. Since the arc of movement for the broom 27 should preferably be on as large a radius as practicable, the arms 31 are preferably of substantial length and extend obliquely upwardly and forwardly. At their forward ends, the arms 31 are provided with respective integral split bearing eyes 33 in rotatable engagement with respective stub shafts 34 and 35 (Figs. 3 and 4) at respectively the right and left sides of the operator's cab 17. A retainer plate 36 is secured to the outer end of the stub 34. In the present instance, the stub shaft 34 is carried by an appropriate bracket structure 37, and the stub shaft 35 by a bracket structure 38 respectively mounted upon the adjacent chassis frame beams 18.

For rotatably driving the sweeper broom 27, a sprocket chain 39 runs over a driven sprocket 40 keyed upon the broom shaft 29 (Fig. 6) and a drive sprocket 41 carried by a stub drive shaft 42 at least in part journaled within a bore 43 in the broom arm stub shaft 34 and having a driven gear 44 keyed thereon and meshing with a drive pinion 45 on a drive shaft 47. Enclosing the gear assembly 44, 45 and the drive shaft 47 is a housing 48 which has an inward tubular extension 49 enclosing a spline clutch assembly 50 arranged to be operated through the medium of an external handle 51 for selectively clutching and declutching the drive shaft 47 and a power shaft 52 which is appropriately driven from the power unit in the power section 15. Power for driving a side broom 53 is also transmitted through the drive

shaft 47 which carries at its outer end a bevel gear 54 meshing with a suitable bevel pinion 55 on a power transmission carried within a housing 57 which supports the side broom 53 and is mounted upon the housing 43.

Sweepings from the brooms 27 and 53 are collected in a bucket structure 58 operatively disposed forwardly of the main broom 27.

In order to provide for slackening the drive chain 39, as when the sweeper broom 27 is to be mounted or removed, and for effecting adequate operating tension in the drive chain, the broom supporting arms 31 are preferably constructed for adjustment as to length and for this purpose may be made from channel stock with the respective forward end portions thereof formed as adjustable heads 59. Each of the heads 59 is formed with an offset rear end portion 60 having longitudinal adjustment slots 61 through which extend studs 62 carried by an adapter block 63 secured as by bolts 64 in the adjacent channeled end portion of the respective broom arm 31. Clamping nuts 65 threaded on the stud 62 and driving against washers 67 secure the offset portion 60 in longitudinally adjusted relation against the fixed adapted block 63, thereby determining the overall length of the broom arm. Any tendency of the slidable adjustment to shorten under the influence of the relative longitudinal forces created in the operation of the drive chain 39 is avoided by an adjustment or stop screw 68 threaded through a lateral ear 69 on the adapter block 63 and bearing against a stop shoulder provided by a lateral integral ear 70 on the head 59. A locking nut 71 carried by the adjusting screw 68 locks it in adjusted condition. By preference each of the heads 59 is provided with a pair of the stop ears 70 extending in opposite directions for purposes of standardization and to enable use of a standard head at either side of the machine.

Means are provided for elevating the main sweeper broom 27 to inactive position as desired by swinging the broom arms 31 about the pivots provided by the stub shafts 34 and 35. According to the present invention, such elevating means include a hydraulic operator 72 (Figs. 2 and 3) of the reciprocating cylinder and piston type having the cylinder thereof secured pivotally at its blind end to a supporting bracket 73 carried by a cross bar 74 the ends of which are fixedly secured to stub shafts 75 which project through the side plates 19. The cross bar and stub shaft assembly is maintained in any suitable manner in fixed, non-rotatable relation to the side plates 19. The cylinder 72 is adapted to be supplied with motivating pressure fluid from any suitable source and controlled in any appropriate manner through respective ducts 77 and extends upwardly for connection of a piston rod 78 projecting therefrom by means of a knuckle 79 with a crank arm 80. By motivating the hydraulic operator 72 to retract the piston rod 78 so that the knuckle 79 assumes the lower broken line position indicated at 79' correspondingly turns a shaft 81 to which the crank 80 is fixedly secured and likewise swings respective actuating arms 82 secured fast upon the respective opposite end portions of the shaft. This action of the arms 82 operates through the medium of articulated links 83 and 84 to swing the respective broom arms 31 upwardly and thus disposes the sweeper broom 27 in its inactive position.

A clevis knuckle 85 connects each of the respective links 83 to its actuating arm 82. A

clevis 87 on the lower end of each of the links 84 is pivotally secured as by means of a pin 88 to a respective angular bracket 89 secured fixedly as by welding to the associated broom arm 31. A mounting for the crank operated shaft 31 is afforded by journal flanges 90 secured to the outer faces of the respective opposite side plates 19 through which the shaft projects. When the hydraulic operator 72 releases the broom actuating mechanism, the broom is allowed, in so far as the hydraulic actuating system is concerned, to rest freely upon the surface to be swept. As the bristles of the broom wear off and the broom gradually swings down about an arc as indicated in Fig. 2, adequate slack in the actuating mechanism allows it to substantially follow the gradually depressed positions of the broom, the piston rod knuckle gradually attaining to a position as indicated at 79'.

An integrated relationship between the main sweeper brush assembly and a pair of side guard or dirt shoes 91 is established through the medium of respective links 92 connected between shoe supporting arm 93 and the adjacent broom arm 31 so that lifting of the sweeper broom will also effect lifting of the dirt shoes. To this end, each of the integrating links 92 is formed in two separable parts, including a headed stud portion 94 which extends longitudinally slidably through a laterally projecting bracket 95 and a swivel pad 97 carried by the bracket and is threadedly assembled with the remainder of the link, being held fixedly in longitudinally adjusted relation thereto by means of lock nuts 98. At its end the link may be provided with a hook 99 engaging a stud 100 on the associated shoe-supporting arm 93. Each of the arms 93 projects forwardly and upwardly and is provided with a journal 101 pivotally engaged upon the adjacent projecting end of the stub shaft 75 at that side of the machine. Thus, when the broom arms 31 are swung upwardly to lift the broom to inactive position, the links 92 will act therewith to similarly swing the dirt shoe arms 93 and thereby lift the dirt shoe members 91 to inactive position. In order to permit a certain amount of independent relative swinging movement of the broom arms 31 relative to the shoe arms 93, both for accommodating such operational relative movement as may be effected by uneven pavement contour, obstructions and the like over which either of the assemblies may be required to pass, and for permitting independent relative downward deflection of the broom arms 31 as the broom 27 wears down, the relationship of the integrating links 92 to the respective brackets 95 is such as to permit a certain amount of relative axial movement of the links and brackets.

Each of the dirt shoes 91 is formed as a vertical plate equipped with a tread 102 and has an inwardly projecting deflector member 103 disposed at an angle to deflect dirt thrown thereagainst by the broom 27 into the dirt bucket 58. A reinforcing strut plate 104 backs up the deflector.

It is desirable that the dirt shoes 91 be permitted to rock within limits in a vertical plane relative to the respective supporting arms 93 and for this purpose a limited rocking connection is afforded between the supporting arms and the respective shoes. Accordingly, the shoe-engaging end of each respective arm 93 is equipped with a journal sleeve 105 engaged for free rocking movement with a stub shaft 107 secured rigidly to the side of the associated shoe 91 as by means of a fixed base plate 108, a cotter pin

109 holding the journal against displacement from the stub shaft. A limit upon relative rocking is attained by the engagement of a laterally protruding rigid stud 110 on the arm 93 engaging within a limit socket 111 of predetermined greater diameter provided therefor fixedly on the base plate 108. Thus, the shoe may rock about the axis of the stub shaft 107 within the limits defined by engagement of the stud 110 within the socket 111.

Since the main sweeper broom 27 and the various structures related thereto, and more especially the broom arms 31 are of necessity of fairly rugged construction and therefore of some weight, this full unrestrained weight imposed upon the relatively small active periphery of the broom in operation tends to cause excessively rapid wearing down of the bristles. According to the present invention, however, a highly advantageous weight reducing or compensating device is employed which does not entirely counterbalance the weight of the broom assembly but allows the broom sufficient sweeping traction while substantially relieving the bristles at the active area of the broom periphery of the unduly wearing weight. Accordingly, each of the broom-supporting arms 31 has connected thereto yieldable compensating means comprising an elongated, extensible coiled spring 112 (Figs. 1, 3 and 5) which is preferably so mounted as to be self-adjustable to maintain fairly uniform operative compensating tension as the broom arms 31 swing to various positions with the broom. For this purpose, the compensating spring 112 for each of the broom arms is connected at one end to the broom arm 31 through the medium of a stud bolt 113 secured to the spring end and engaging within any selected one of a vertically transverse series of apertures 114 in a connecting bracket 115 fixedly secured at an intermediate point to the outer side of the associated arm at preferably about the longitudinal center of the arm. The center of pull of the compensating spring can, therefore be determined by selection of the bracket aperture 114 for optimum results with any given assembly, and in particular with respect to the length or particular tension of any spring which may vary somewhat in any pair of springs. Thus, the adjustment indicated is advantageous to secure a proper balance between the pair of compensating springs 112 in the machine.

Each of the compensating springs 112 preferably extends upwardly in somewhat divergent relation to the associated broom arm 31 so as to impose an oblique compensating thrust and is connected to the rear end of a self-adjusting, tensioning link or arm 117, the opposite or forward end of which is pivotally secured to means 60 which support it in relatively free rocking relation to adjacent structure to permit a full range of rocking adjustment. At the right side of the machine, this means may comprise an upstanding ear 118 formed with an integral bracket 65 structure 119 secured to the housing 48 and with the adjusting arm 117 freely overlying the housing. At the left side of the machine (Figs. 3 and 4) an upstanding arm 120 affords a pivotal support for the rocking arm 117 at that side on 70 a common axis with the support afforded by the ear 118 at the opposite side of the machine. As a matter of convenience, the supporting arm 120 may be formed with an integral mounting sleeve 121 which is received upon an outwardly projecting reduced diameter section 122 of the stub

to which the sleeve 121 is keyed in proper position and upon which it is retained by means of a retainer plate 123 secured as by means of screws 124 on the end of the stub extension. It may be noted that the pivotal mounting axis of the compensating spring arms 117 is disposed above and forwardly of the pivotal axis of the broom arms 31, thus affording a highly efficient compensating action in the spring arms.

As best shown in Fig. 2, as the broom arms 31 swing up or down, appropriate corresponding swing of the self-adjustable rocking arms 117, as induced by the tension of the associated compensating spring 112, assures that the spring tension will remain reasonably uniform, particularly in the various operative or sweeping positions attained by the broom 27.

It will, of course, be understood that various details of construction may be varied through a wide range without departing from the principles of this invention, and it is, therefore, not the purpose to limit the patent granted hereon otherwise than necessitated by the scope of the appended claims.

I claim as my invention:

1. In combination in a street sweeping machine, a support structure, a main broom, an oblique arm carrying said broom at one end, a pivot connecting the other end of said arm to said support structure to allow raising and lowering of said arm and broom, said arm being longitudinally adjustable, means for maintaining the longitudinal adjustment of said arm in opposition to a generally longitudinal thrust on said arm tending to shorten said arm, and a counterbalancing tensioned spring connected to a medial point on said arm and secured to said support structure immediately above and beyond said pivot to have a length in the raised position of said arm greater than the length of said arm from said medial point to said pivot and to define a small acute angle between the arm and the counterbalancing tension spring and to apply substantially the same torque on said arm for counterbalancing the weight of said broom in both its raised inactive position and its lowered brushing position.

2. In combination in a street sweeping machine, a support structure, a main broom, an arm carrying said broom at one end, a pivot connecting the other end of said arm to said support structure to allow raising and lowering of said arm and broom, means secured to said arm and to said support structure for raising said broom through a narrow angle, and a counterbalancing tensioned spring independent of said raising means and connected to a point on said arm and secured to said support structure immediately above and beyond said pivot to have a length in the raised position of said arm greater than the length of said arm from said point to said pivot, said counterbalancing spring applying substantially uniform torque to said arm and said broom in any position thereof to relieve the bristles of the broom of the weight of the broom and the arm in any lowered active position of the broom and to relieve the raising means of the weight of the broom and arm in the raised inactive position of the broom.

3. In combination in a street sweeping machine, a support structure, a main broom, an oblique arm carrying said broom at one end, a pivot connecting the other end of said arm to said support structure to allow raising and lowering of said arm and broom, means secured to

said arm and to said support structure for raising said broom, said raising means including a lost motion connection to said arm to isolate said raising means from motions of said arm in its lowered position, and a counterbalancing tensioned spring independent of said raising means and connected to a medial point on said arm and secured to said support structure immediately above and beyond said pivot to have a length in the raised position of said arm greater than the length of said arm from said medial point to said pivot and to define a small acute angle between said arm and said spring, said counterbalancing spring applying substantially uniform torque to said arm and said broom in any position thereof to relieve the bristles of the broom of the weight of the broom and the arm in any lowered position of the broom and to relieve the raising means of the weight of the broom and arm in the raised inactive position of the broom.

4. In combination in a street sweeping machine, a support structure, a main broom, an oblique arm carrying said broom at one end, a pivot connecting the other end of said arm to said

25 support structure to allow raising and lowering of said arm and broom, means for raising and lowering said broom including power cylinder means secured to said support structure and an articulated member connected to said power cylinder means and to said arm and tensioned by

30 said power cylinder means to raise said arm, said articulated member being sufficiently slack in the lowered brushing position of said broom to allow free movement to said arm, and a counterbalancing tensioned spring independent of said raising means and connected to a medial point on said arm and secured to said support structure immediately above and beyond said pivot to have a length in the raised position of said arm greater than the length of said arm from said medial point to said pivot and to define a small acute angle between said arm and said spring, said counterbalancing spring applying substantially uniform torque to said arm and said broom in any position thereof to relieve the bristles of the broom of the weight of the broom and the arm in any lowered active position of the broom and to relieve the raising means of the weight of the broom and arm in the raised inactive position of the broom.

45 5. In combination in a street sweeping machine, a support structure, a rotary main sweeping broom, means for rotating said broom, supporting arms pivotally mounted from said structure at one end of each thereof and supporting said broom at the other end of each, means for swingingly elevating said arms through a narrow angle to carry the broom into inactive position, dirt shoes adjacent the opposite ends of the broom, arms pivotally mounting said dirt shoes on said structure, means connecting the broom supporting arms and the shoe supporting arms for effecting elevation of the shoes by upward swinging of the shoe supporting arms when the broom supporting arms are swung up for elevating the broom, and counterbalancing tension

55 springs independent of said means for swingingly elevating said broom supporting arms and connected at one end of each thereof respectively to a medial point on said broom supporting arms, the other end of each of said counterbalancing tension springs respectively connected to said supporting structure immediately above and beyond the pivotal mounting for said broom supporting arms thereby defining a small

acute angle between said counterbalancing tension springs and said supporting arms respectively, the counterbalancing tension springs operating upon said broom supporting arms to support the weight thereof and the broom assembly and applying substantially uniform torque to said arms and broom assembly in all positions thereof, thereby relieving the bristles of said broom of the weight of the broom assembly when the broom is in its active position and relieving the elevating means of the weight of said supporting arms and broom assembly when placed in inactive position.

6. In combination in a street sweeping machine, a support structure, a rotary main sweeping broom, means for rotating said broom, support arms pivotally mounted from said structure at one end of each thereof and supporting said broom at the other end of each, means for swingingly elevating said arms to carry the broom into inactive position, said means for swingingly elevating said arms including a lost motion connection to said arms to isolate said means from motions of said arms in its active position, dirt shoes adjacent the opposite ends of the broom, arms pivotally mounting said dirt shoes on said structure, means connecting the broom support arms and the shoe support arms for effecting elevation of the shoes by upward swinging of the shoe support arms when the broom support arms are swung up for elevating the broom, and counterbalancing tension springs connected at one end of each thereof respectively to medial points on said broom support arms, the other end of said counterbalancing tension springs respectively connected to said support structure immediately above and beyond the pivot mounting for said support arm thereby defining a small acute angle between said counterbalancing tension spring and said support arms respectively, the counterbalancing tension springs operating upon said broom support arms to support their weight thereof and the weight of said broom assembly and applying substantially uniform torques to said arms and said broom assembly in all positions thereof, thereby relieving the bristles of said broom of the weight of the broom assembly when the broom is in its active position and relieving the elevating means of the weight of said broom assembly when placed in inactive positions.

7. In combination in a street sweeping machine, a support structure, a rotary main sweeping broom, means for rotating said broom, support arms pivotally mounted from said structure at one end of each thereof and supporting said broom at the other end of each, means for swingingly elevating said broom support arms to carry the broom into inactive position, an articulated member connected to said elevating means and to said arms and tensioned by said elevating means to raise said arms, said articulated member being sufficiently flexed in the active brushing position of said broom to allow free movement of said arms, dirt shoes adjacent the opposite ends of the brooms, arms pivotally mounting said dirt shoes on said structure, means connecting the broom support arms and shoe support arms for effecting elevation of the shoes by upward swinging of the shoe support arms when the broom support arms are swung up for elevating the broom, and counterbalancing tension springs connected at one end of each thereof respectively to a medial point on said broom support arms, the other ends of said counterbal-

ancing tension springs respectively connected to said support structure immediately above and beyond the pivot mounting for said broom support arms thereby defining a small acute angle between said counterbalancing tension springs and said support arms respectively, the counterbalancing tension springs operating upon said support arms to support the weight thereof and said broom assembly and applying substantially uniform torques to said broom assembly in all positions thereof, thereby relieving the bristles of said broom of the weight of the broom assembly when the broom is in its active position and relieving the elevating means of the weight of said broom assembly when placed in inactive position.

8. In combination in a street sweeping machine, a support structure, a main broom, an oblique arm carrying said broom at one end, a pivot connecting the other end of said arm to said support structure to allow raising and lowering of said arm and broom, a dirt deflecting shoe, a pivoted shoe supporting arm, a pivotal connection between the shoe supporting arm and the shoe to permit relative rocking movement of the shoe for self-adjustment to the surface over which it travels and interengaging means on the shoe and the shoe supporting arm for limiting said rocking movement, means interconnecting said shoe supporting arm and the broom carrying arm to raise said shoe when said broom is raised, a counterbalancing tensioned spring connected to a medial point on said arm and secured to said support structure immediately above and beyond said pivot at said other end of said arm to have a length in the raised position of said arm greater than the length of said arm from said medial point to said pivot at said other end of said arm and to define a small acute angle between the arm and the counterbalancing tension spring and to apply substantially the same torque on said arm for counterbalancing the weight of said broom in both its raised inactive position and its lowered brushing position.

9. In combination in a street sweeping machine, a support structure, a rotary main sweeping broom, means for rotating said broom, support arms pivotally mounted from said structure at one end of each thereof and supporting said broom at the other end of each, said broom support arm being longitudinally adjustable, means for maintaining the longitudinal adjustment of said broom support arm in opposition to a generally longitudinal thrust thereon tending to shorten said broom support arms, means for swingingly elevating said broom support arms to carry the broom into inactive position, an articulated member connected to said elevating means and to said arms and tensioned by said elevating means to raise said arms, said articulated member being sufficiently flexed in the active brushing position of said broom to allow free movement of said arms, dirt shoes adjacent the opposite ends of the brooms, arms pivotally mounting said dirt shoes on said structure, a pivotal connection between the shoe support arms and the shoes to permit relative rocking movement of the shoe for self-adjustment to the surface over which it travels, interengaging means on the shoes and the shoe support arms for limiting said rocking movement, means connecting the broom support arms and shoe support arms for effecting elevation of the shoes by upward swinging of the shoe support arms when the broom support arms are swung up for elevating the broom, and counterbalancing tension springs

connected at one end of each thereof respectively to a medial point on said broom support arms, the other ends of said counterbalancing tension springs respectively connected to said support structure immediately above and beyond the pivot mounting for said broom support arms thereby defining a small acute angle between said counterbalancing tension springs and said support arms respectively, the counterbalancing tension springs operating upon said support arms to support the weight thereof and said broom assembly and applying substantially uniform torques to said broom assembly in all positions thereof, thereby relieving the bristles of said broom of the weight of the broom assembly when the broom is in its active position and relieving the elevating means of the weight of said broom assembly when placed in inactive position.
